DOG BLANKET

Olga P. Gajda, 707 W. Junior, Chicago, Ill.

Filed Jan. 26, 1959, Ser. No. 54,291

Term of patent 14 years

(Cl. D38—10)

Fig. 1 is a plan view of a dog blanket showing my new design; and

Fig. 2 is a vertical cross sectional view on the line 2—2 of Figure 1.

I claim:

The ornamental design for a dog blanket, substantially as shown.
